(57) **CLAIM**

The ornamental design for the pliers handles, as shown and described.

DESCRIPTION

FIG. 1 is a first side view of a first embodiment of the pliers handles with jaws of the pliers in a first position;

FIG. 2 is a second side view of the pliers handles of FIG. 1;

FIG. 3 is a first end view of the pliers handles of FIG. 1;

FIG. 4 is a second end view of the pliers handles of FIG. 1;

FIG. 5 is a top view of the pliers handles of FIG. 1;

FIG. 6 is a bottom view of the pliers handles of FIG. 1;

FIG. 7 is a side view of the pliers handles of FIG. 1 with jaws of the pliers in a second position;

FIG. 8 is a side view of the pliers handles of FIG. 1 with jaws of the pliers in a third position;

FIG. 9 is a first side view of a second embodiment of the pliers handles with jaws of the pliers in a first position;

FIG. 10 is a second side view of the pliers handles of FIG. 9;

FIG. 11 is a first end view of the pliers handles of FIG. 9;

FIG. 12 is a second end view of the pliers handles of FIG. 9;

FIG. 13 is a top view of the pliers handles of FIG. 9; and,

FIG. 14 is a bottom view of the pliers handles of FIG. 9.

The broken lines in the drawings illustrate the environment of the claimed design and form no part thereof.

1 Claim, 10 Drawing Sheets
